(57) **CLAIM**

What is claimed is the ornamental design for a disc jockey console, as shown and described.

DESCRIPTION

FIG. 1 is a front perspective view of a disc jockey console, showing the new design;

FIG. 2 is a rear perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof; and,

FIG. 7 is a bottom plan view thereof.

The broken lines showing a pair of sheet holders in FIGS. 1 and 2 depict environmental matter, and form no part of the claimed design.
